UNITED STATES PATENT OFFICE

REINHARD HILDEBRAND, OF WEBSTER GROVES, MISSOURI, ASSIGNOR TO FULTON IRON WORKS COMPANY, OF ST. LOUIS, MISSOURI, A CORPORATION OF DELAWARE

REVERSING MECHANISM FOR INTERNAL COMBUSTION ENGINES

Application filed February 10, 1930. Serial No. 427,114.

This invention relates generally to reversing mechanisms of the kind employed particularly in connection with engines of the Diesel type for changing the direction of rotation of the crank shaft, and particularly to reversing mechanisms of the type in which the change in direction is effected by changing the operative relationship between the rocker arms, or valve-actuating devices, and two separate and distinct sets of cams on the cam shaft, one of which cooperates with the rocker arms when the crank shaft is rotating in one direction and the other when the crank shaft is rotating in the opposite direction, the predominant object of the invention being to provide a mechanism of this type which is very simple in construction and extremely efficient in operation.

Another object of the invention is to provide a reversing mechanism of the type referred to which is simplified by utilizing the rocker arm shaft of the engine as the supporting and actuating shaft of the reversing mechanism. In other words, the rocker arm shaft of an engine equipped with my improved reversing mechanism performs a dual function in that it acts (a) in its original capacity as the rocker arm shaft, and (b) serves as the supporting shaft and means for actuating the reversing mechanism.

Fig. 1 is a plan view of a portion of an engine of the Diesel type equipped with my improved reversing mechanism.

Fig. 2 is a section on line 2-2 of Fig. 1.

Fig. 3 is a sectional detail illustrating one of the roller arms of the improved reversing mechanism and indicating the manner in which the rolls are associated therewith.

Fig. 4 is a section on line 4-4 of Fig. 3.

In the drawings, wherein is shown for the purpose of illustration, merely, one embodiment of the invention, A designates the rocker arms, or valve-actuating devices, of an engine of the Diesel type, and B designates a cam shaft on which cams are mounted which

actuate the rocker arms. The crank shaft (not shown) of the engine is operatively connected in the usual manner with the cam shaft B. In order that the direction of rotation of the crank shaft of the engine may be reversed the cam shaft B is provided with sets of cams, there being a pair of such cams cooperatively associated with each rocker arm A; that is to say, each rocker arm A has associated with it a cam 1 with which said rocker arm is caused to cooperate when it is desired to have the crank shaft rotate in one direction, and another cam 2 with which the rocker arm is caused to cooperate when it is desired to have the crank shaft rotate in the opposite direction.

The rocker arms of the engine illustrated in the drawings are mounted in the usual manner on the rocker arm shaft C; that is to say, the rocker arm shaft C serves as a fulcrum member on which said rocker arms are loosely mounted for pivotal movement, and end portions A' of said rocker arm are arranged to actuate certain valves of the engine. At the end of each rocker arm opposite to the end A' thereof I pivotally attach at the point 3 thereof an arm 4, said arm being extended downwardly from its point of pivotal connection toward the cam shaft B. The arms 4, preferably, comprise each a pair of spaced arm elements 4' (Fig. 4) which are connected together by a transverse bar 5 so that a unitary arm structure is provided, and the lower end of each arm element is flared outwardly, as shown in Fig. 3. Disposed between the lower portion of the arm elements 4' of each arm 4 is a pair of rollers 6 and 7, said rollers 6 and 7 being offset transversely of the arm with respect to each other, and being arranged in overlapping relation. The rollers 6 and 7 are mounted for rotary movement on short shafts 8 and 9 which are supported by the lower end portions of the spaced arm elements 4', and said rollers are maintained in their proper longitudinal positions on said

short shafts by spacing collars, which are cut away as indicated at 10 in Fig. 3 so as to avoid interference between said collars and said rollers 6 and 7.

5 The spacing of the rollers 6 and 7 transversely of the arms 4 is such that said rollers are alined vertically with the cams 1 and 2 on the cam shaft B; in other words, the cam 1 and the roller 6, and the cam 2 and the roller 7, respectively, will be alined vertically. In this connection it will be noted by referring to Fig. 2 that only one of each pair of rollers 6 and 7 associated with an arm 4 will be in contact with a cam on the cam shaft B at any time, the arrangement of said rollers being such that it is not possible to bring both rollers associated with an arm 4 into cooperation with both of the cams on the cam shaft B with which said rollers are adapted to cooperate.

10 20 The rocker arm shaft C is arranged for axial rotation and is provided with a hand wheel C' (Fig. 2) or other suitable means for effecting such rotation, and mounted on said rocker arm shaft at points adjacent to each 25 of the rocker arms A is a pair of spaced eccentrics 11. The eccentrics 11 are provided with split collar portions 12 with which clamping bolts 13 are associated, whereby said eccentrics are rigidly fixed to said rocker 30 arm shaft. Associated with each eccentric 11 in the usual manner is an eccentric strap 14, said eccentric strap being provided with an arm portion 15 which extends toward the 35 associated arm 4, and said arm portion is provided with a clamping portion 15' at its extreme outer end. By referring to Fig. 1 it will be noted that the eccentrics of an associated pair of eccentrics are located immediately adjacent to the opposite side faces of the 40 associated rocker arm A, and the clamping portions 15' at the outer ends of the arm portions 15 of a pair of associated eccentric straps 14 are clamped, by means of the bolts 16, to the opposite outer end portions of the short 45 shaft 8 of the associated arm 4 (Fig. 4).

In the operation of an engine equipped with my improved reversing mechanism the rocker arm shaft C may be rotated axially to cause the eccentrics 11, through the instrumentality of the eccentric straps 14 and arm portions 15, to swing the roller arms 4 on their pivots 3. Such movement of the arms 4 will result in said arms being moved from the position illustrated in Fig. 2, where the roller 50 6 is in cooperative engagement with the cam 1, to a position where the roller 7 would be in cooperative engagement with the cam 2 and said roller 6 would be out of engagement with the cam 1. In like manner by reverse rotation of the rocker arm shaft the arm 4 may be moved from a position where the roller 7 is in cooperative engagement with the cam 2 to a position where the roller 6 is in 55 cooperative engagement with the cam 1 and

the roller 7 is out of engagement with the cam 2.

It is obvious, therefore, that at the will of the operator of an engine equipped with my improved reversing mechanism the direction of rotation of the crank shaft thereof may be reversed by a simple partial rotation of the rocker arm B.

I claim:

1. An internal combustion engine comprising a cam shaft on which cams are mounted for regulating the direction of operation of the engine, valve-actuating rocker arms, cam-engaging rollers associated with said rocker arms, means for pivotally connecting said rollers to said rocker arms, and means for adjusting the positions of said rollers so as to cause predetermined cams on the cam shaft to be engaged by certain rollers associated with the rocker arms, said means for adjusting the positions of the rollers comprising an eccentrically actuated member connected to said means for pivotally connecting the rollers to the rocker arms.

2. An internal combustion engine comprising a cam shaft on which cams are mounted for regulating the direction of operation of the engine, valve-actuating rocker arms, a rocker arm shaft for supporting said rocker arms, cam-engaging rollers associated with said rocker arms, means for pivotally connecting said rollers to said rocker arms, and means for adjusting the positions of said rollers so as to cause predetermined cams on the cam shaft to be engaged by certain rollers associated with the rocker arms, said means for adjusting the positions of the rollers comprising an eccentrically actuated member mounted on said rocker arm shaft and connected to said means for pivotally connecting the rollers to the rocker arms.

3. An internal combustion engine comprising a cam shaft on which cams are mounted for regulating the direction of operation of the engine, valve-actuating rocker arms, a rocker arm shaft for supporting said rocker arms, cam-engaging rollers associated with said rocker arms, means for pivotally connecting said rollers to said rocker arms, and means for adjusting the positions of said rollers so as to cause predetermined cams on the cam shaft to be engaged by certain rollers associated with the rocker arms, said means for adjusting the positions of the rollers comprising an eccentrically actuated member mounted on said rocker arm shaft and connected to said means for pivotally connecting the rollers to the rocker arms, said rocker arm shaft being rotatable to impart movement to said roller-adjusting means.

4. An internal combustion engine comprising a cam shaft on which cams are mounted for regulating the direction of operation of the engine, valve-actuating rocker arms, a rocker arm shaft for supporting said rocker

arms, cam-engaging rollers associated with said rocker arms, means for pivotally connecting said rollers to said rocker arms, and means for adjusting the positions of said rollers so as to cause predetermined cams on the cam shaft to be engaged by certain rollers associated with said rocker arms, the last-mentioned means including an eccentric mounted on said rocker arm shaft, and a member cooperable with said eccentric and connected to said means for connecting the rollers to the rocker arms, whereby said means may be subjected to movement in response to rotary movement of the rocker arm shaft.

15 In testimony that I claim the foregoing I hereunto affix my signature.

REINHARD HILDEBRAND.
